[57] CLAIM

The ornamental design for a wrench, as shown and described.

DESCRIPTION

FIG. 1 is a perspective view of a wrench showing my new design.

FIG. 2 is a top plan view of the wrench of FIG. 1.

FIG. 3 is a bottom plan view of the wrench of FIG. 1.

FIG. 4 is a side elevational view of the wrench of FIG. 1, it being understood that the opposite side is a mirror image thereof.

FIG. 5 is a left end elevational view of the wrench as it appears in FIG. 4.

FIG. 6 is a right end elevational view of the wrench as it appears in FIG. 4.
